(57) **CLAIM**

The ornamental design for a puff tag, as shown and described.

DESCRIPTION

FIG. 1 is a top perspective view of a puff tag in accordance with the new design;

FIG. 2 is a bottom plan view thereof;

FIG. 3 is a right side elevation view thereof, a left side elevation view being a mirror image thereof;

FIG. 4 is a front view thereof; and,

FIG. 5 is a rear view thereof.

The broken lines shown in FIGS. 1-4 represent boundaries of the design, with the lines themselves and the areas within them forming no part of the claimed design.
